UNITED STATES PATENT OFFICE

LAWRENCE M. BAYAN, OF PROVIDENCE, RHODE ISLAND, ASSIGNOR TO C. G. KING & CO., INC., OF PROVIDENCE, RHODE ISLAND

DESIGN FOR A SHOE ORNAMENT

Application filed May 8, 1931. Serial No. 39,776. Term of patent 3½ years.

To all whom it may concern:

Be it known that I, LAWRENCE M. BAYAN, a citizen of the United States, residing at Providence, in the county of Providence, and State of Rhode Island, have invented a new, original, and ornamental Design for Shoe Ornaments, of which the following is a specification, reference being had to the accompanying drawings, forming part thereof.

In said drawings, Fig. 1 is a front face view, and Fig. 2 is an edge view of a shoe ornament, showing my new design.

I claim:

The ornamental design for a shoe ornament as shown.

Signed at Providence, in the county of Providence and State of Rhode Island, this 7th day of May, A. D. 1931.

LAWRENCE M. BAYAN.
